UNITED STATES PATENT OFFICE.

THOMAS W. SNELL, OF CHICAGO, ILLINOIS.

CENTER SUPPORT OR HANGER.

SPECIFICATION forming part of Letters Patent No. 468,705, dated February 9, 1892.

Application filed June 2, 1891. Serial No. 394,845. (No model.)

To all whom it may concern:

Be it known that I, THOMAS W. SNELL, of Chicago, in the county of Cook and State of Illinois, have invented a new and Improved 5 Center Support or Hanger, of which the following is a full, clear, and exact description.

The object of the invention is to provide a new and improved device for supporting centers for masonry, arches, floors, and the like, 10 and which is simple and durable in construction, can be readily applied and easily adjusted to support the center at the proper place.

The invention consists of a chain carrying 15 a cross-bar adapted to engage the center, a bolt provided with a hook adapted to be engaged by the said chain, and a cross-beam adapted to carry the said bolt.

The invention also consists of certain parts 20 and details and combinations of the same, as will be fully described hereinafter, and then pointed out in the claims.

Reference is to be had to the accompanying drawings, forming a part of this specification, 25 in which similar letters of reference indicate corresponding parts in both the figures.

Figure 1 is a side elevation of the improvement as applied, parts being in section; and Fig. 2 is a plan view of the same.

30 The improved center support or hanger comprises a bolt A, formed on its lower end with a hook B, and passing at its upper end through a transversely-extending slot C', formed in the cross-beam C, which is supported on the I-beams D, extending at right angles to the cross-beam C. The upper end of the bolt A passes through a washer E, held on top of the cross-beam C, as is plainly shown in the drawings, the said washer being engaged on top by the nut F of the bolt A, so 35 as to raise or lower it.

The hook B is adapted to be engaged by one of the twisted links of a chain G, extending downward therefrom and passing through 45 a longitudinal slot H', formed in the center H, of any approved construction. The lower-most link in the chain G supports the cross-bar I, adapted to engage the under side of the center H and having its end I' turned slightly 50 upward, so as to prevent displacement of the cross-bar on the under side of the center H.

In order to hold the center H in place, two or more devices, such as shown in Fig. 1, are

connected with the center H, each cross-bar I engaging the under side of the center, the 55 chain extending upward and hooking onto the hook B of the respective bolt A. The latter is then raised or lowered by turning the nut F until the center H is raised or lowered to the desired place. The planks J are then 60 placed across the top of the center H to form the floor or center upon which the masonry-work is to rest.

It is understood that the chain G is first 65 adjusted on the hook B, so as to bring the center H as near to its correct place as possible, and then by adjusting the nut F to raise or lower the bolt A the chain G, bar I, and the center H supported thereon, are brought to the exact position.

70 My center support or hanger always passes through the center of the arch in the tile-course, and a hole is always left from nine to eighteen inches long by six to nine inches wide, and this hole is filled up after the centers are dropped.

75 It will be seen that this device is very simple and durable in construction and can be readily applied and easily adjusted to support the center at the proper place. The device can also be conveniently folded up for transportation from one place to another.

Having thus described my invention, I claim as new and desire to secure by Letters Patent—

85 1. A center support or hanger comprising a chain carrying a cross-bar adapted to engage the center, a bolt provided with a hook adapted to be engaged by the said chain, and a cross-beam for carrying the said bolt, substantially as shown and described.

90 2. In a center support or hanger, the combination, with a slotted cross-beam, of a bolt passing through the slot of the said cross-beam and having its nut resting on a washer held on top of the said cross-beam, a chain 95 engaging a hook on the lower end of the said bolt, and a cross-piece held on the said chain and adapted to engage the center to support the latter, substantially as shown and described.

100 THOMAS W. SNELL.
